[57] CLAIM

The ornamental design for a dust collection member, as shown and described.

DESCRIPTION

FIG. 1 is a first perspective view, taken from the front and to the right, of the dust collection member of the present invention, shown installed on a miter saw having the features depicted in broken lines;

FIG. 2 is second perspective view, taken from the front and to the left, of the invention illustrated in FIG. 1, shown installed on a miter saw having the features depicted in broken lines;

FIG. 3 is a third perspective view, taken from the front and to the left, and in isolation, of the invention shown in FIG. 1

FIG. 4 is a fourth perspective view, taken from the front and to the right, and in isolation, of the invention shown in FIG. 1;

FIG. 5 is a left side elevational view of the invention shown in FIG. 1;

FIG. 6 is a right side elevational view of the invention shown in FIG. 1;

FIG. 7 is a front elevational view of the invention shown in FIG. 1;

FIG. 8 is a rear elevational view of the invention shown in FIG. 1;

FIG. 9 is top view of the invention shown in FIG. 1; and, FIG. 10 is a bottom view of the invention shown in FIG. 1. The features shown in broken lines in FIGS. 1 and 2 are for the purpose of showing an environment in which the present invention may be used, for illustrative purposes only, and do not form a part of the claimed design.
